15 Claims. (Cl. 128—525)

ABSTRACT OF THE DISCLOSURE

Brassiere fabricated of light-weight material, such as nylon-tricot to provide an unusual degree of softness, flexibility, pliability, and the characteristics of invisibility through an outer garment, as well as enabling the bust to in effect appear naturally, comprising a plurality of breast receiving portions, each having an apex and a generally curvilinear side dart efftending from one terminal location disposed laterally to one side of the apex of said portion and within an upper half of said portion to another terminal location disposed laterally to another side of that apex and within a lower half of said breast receiving portion.

The present invention pertains, generally, to brassieres, and more particularly to a brassiere that is so constructed and arranged as to present more than adequate support for the bust, and, in addition, enables the garment to be worn in complete comfort, notwithstanding natural bodily movements.

The designer of women's undergarments, and in particular, brassieres, is constrained to incorporate into a construction thereof such characteristics as will enable it to perform the function of supporting the breast in a desirable and comfortable position. At the same time, the brassiere must be aesthetic in appearance, and in particular, must not be of such a construction as to enable it to be visualized through outer garments, so that all-in-all the female torso or figure will be enhanced. And, in addition to performing the functions of molding and supporting the breast to enhance the natural bodily contours, while at the same time being completely comfortable during use, the brassiere must be capable of protecting such outer garments, as well as the epidermal tissue, from irritation, abrasion and the like, which may result from movement of the brassiere or undergarment relative thereto.

Heretofore, it has been considered necessary to avoid utilizing materials that are flexible and of unusually light-weight for the formation of the breast pockets or breast receiving portions of a brassiere, since, while the material might fit snugly over the breasts, it would not have sufficient body to obtain the form fitting qualities particularly upon bodily movement, and would not afford substantial natural supports for the breasts. At the same time, it has been realized that if the material is too rigid, the breast pockets or breast receiving portions will not present the desirable and requisite characteristics of sufficient softness, flexibility, pliability, and the like, which while being capable of performing the function of adequate support will not be capable of performing the functions of enabling the brassiere to be worn in complete comfort at all times, notwithstanding natural bodily movements, substantially completely in the absence of any irritation or abrasion to the epidermal tissue of the torso adapted to be encompassed by the brassiere. As a result, while the desire to fabricate a garment of this type of an unusually light-weight material has never subsided, a compromise is usually effected, oftentimes involving complicated details of construction with attendant increased costs of material, fabrication, and the like.

Having in mind each and every one of the foregoing

2

considerations, and others that will be readily apparent to those skilled in the art, it will be understood that a primary object of the present invention is to provide an undergarment particularly adapted to be worn upon the female torso, and more particularly, a brassiere, that is fabricated of an unusually light-weight material, and yet is so constructed and arranged as to present the characteristics of providing more than adequate support for the breasts, enabling the brassiere to mold the same and enhance the natural bodily contours of the female torso, while at the same time presenting the characteristics of being able to provide complete comfort to the epidermal tissue of the female torso, notwithstanding natural bodily movements thereof, and protection to the outer garments.

Another primary object of this invention, in addition to the foregoing objects, is to provide an undergarment particularly adapted to be worn upon the female torso, and more particularly a brassiere, that is fabricated of an unusually light weight material, and yet is so constructed and arranged as to admirably perform the functions of molding and supporting the bust, thus enhancing the natural bodily contours of the female torso, while yet being exceedingly comfortable during use, notwithstanding normal bodily movements, said brassiere nevertheless having certain very desirable aesthetic characteristics, such as being invisible through an outer garment to avoid deleteriously effecting the exterior appearance of the female torso, and a see-through quality enabling the bust to in effect, be presented in "nature's own way," while yet being susceptible to ordinary and conventional laundering processes without being subjected to any harmful effects.

Yet another primary object of the present invention, in addition to each and every one of the foregoing objects, is to provide an undergarment particularly adapted to be worn by the female, and more particularly a brassiere, that is capable of fabrication of an unusually light-weight material, and yet is so constructed and arranged as to be capable of presenting the necessary and requisite characteristic of strength, enabling the brassiere to more than adequately perform the functions of molding and supporting the bust, to enhance the natural bodily contours, while yet presenting the characteristics of softness, flexibility and pliability, enabling the brassiere to be exceedingly comfortable to wear in the absence of any irritation or abrasion to the epidermal tissue of the torso encompassed thereby, or to an outer garment supported thereupon, further enabling the brassiere to accommodate maximum freedom of natural bodily movements, said brassiere nevertheless being capable of fabrication by known brassiere manufacturing apparatus, procedures, techniques, and the like, so as to result in a substantial capital-requirement saving on the part of the manufacturer.

A further primary object of the present invention is to provide an undergarment particularly adapted to be worn upon the female torso, and more particularly a brassiere, that is fabricated of an unusually light-weight material, and yet is so constructed and arranged as to present the characteristic of sufficient strength, enabling the brassiere to admirably perform the functions of molding and supporting the breast to enhance the natural bodily contours, while yet presenting the characteristics of softness, flexibility and pliability, enabling the brassiere to be worn in complete comfort during use notwithstanding natural bodily movements, and in the absence of irritation or abrasion to the epidermal tissue of the torso encompassed thereby, said brassiere further enabling maximum circulation of air to substantially decrease the problem of perspiration and the attendant harmful effects to outer garments, and being further so

constructed and arranged as to be applicable to a conventional brassiere with both shoulder and thorax-engirdling straps, a brassiere with only thorax-engirdling straps or bands, a brassiere without straps of any kind, and to breast-supporting and forming cups separate from one another; it will be understood, therefore, that a brassiere constructed in accordance with the principles of the present invention is useful in connection with any torso-encircling government which includes as a part thereof a brassiere.

The invention resides in the combination, construction, arrangement and disposition of the various component parts and elements incorporated in an improved brassiere constructed in accordance with the principles of this invention. The present invention will be better understood and objects and important features other than those specifically enumerated above will become apparent when consideration is given to the following details and description, which when taken in conjunction with the annexed drawing describes, discloses, shows and illustrates a preferred embodiment of the present invention and what is presently considered to be the best mode of practicing the principles thereof. Other embodiments or modifications may be suggested to those having the benefit of the teachings herein, and such other embodiments or modifications are intended to be reserved especially as they fall within the scope and spirit of the subjoined claims.

In the drawing:

FIG. 1 is a front elevational view of a brassiere constructed in accordance with the principles of the present invention; and

FIG. 2 is a rear elevational view, drawn to an enlarged scale, of the brassiere illustrated in FIG. 1.

With reference now to the drawing, there is illustrated therein an undergarment particularly adapted to be worn upon the female torso, and more particularly a brassiere, generally designated by the reference character 10, and constructed in accordance with the principles of the present invention. As shown in the drawing, the present invention is applied to a brassiere comprising shoulder and thorax-engirdling straps or bands, as will hereinafter be described, though it will be understood, as pointed out above, that this invention is equally applicable to a brassiere having only thorax-engirdling straps, a brassiere without straps or bands of any kind, or, for that matter, any torso-encircling government which includes as a part thereof a brassiere.

The undergarment or brassiere comprises a plurality of bust cups or breast receiving cups 12 and 14 that are particularly adapted to be operatively associated with one another. To this end, the bust cups are disposed in a partially overlapping relationship with respect to one another generally frontally of the garment 10, thus defining a panel 16 of generally diamond-shaped configuration, comprising a multiplicity or plurality of layers of material. The layers of material comprising the panel 16 are connected to one another through the medium of double rows of stitching 18 and 20 extending along the periphery of this panel, and along the periphery of each of the cups 12 and 14 generally frontally thereof, and around towards the rear of the garment. The bust or breast receiving cups 12 and 14 themselves comprise a breast receiving portion 22 and 24, respectively, and thorax-engirdling portions 26 and 28, respectively. As is considered readily apparent, the thorax-engirdling portions 26 and 28, when taken in conjunction with the breast receiving portions 22 and 24, enables the presentation of a complete foundation garment of this type which can properly and firmly be positioned upon a corresponding portion of the female torso to perform its intended functions. The double rows of stitching 18 and 20, as is also considered readily apparent, enables the garment or brassiere 10 to present the characteristic of durability, and precludes unraveling of the material, hereinafter to be de-

scribed, from which the breast receiving cups 12 and 14 are particularly adapted to be fabricated.

The garment or brassiere 10 comprises, further, a thorax-engirdling strap or band 30 which is particularly adapted to be connected to the garment completely along the lower peripheral edge of each of the cups 12 and 14. The strap or band 30 may be fabricated of any suitable material, and preferably is fabricated of an elastic material that is distensible in at least one of a plurality of directions, particularly, longitudinally thereof. This strap or band is particularly adapted to extend about and rearwardly of that portion of the female torso particularly adapted to be encompassed thereby, and comprises at its termini disposed generally rearwardly of the garment fastener structure (not shown), for removably operatively connecting the termini one to the other, enabling the garment to be removably positioned upon the female torso, in a known manner. Shoulder straps 32 and 34, which may be fabricated of any suitable material, are operatively connected to the breast receiving cups 12 and 14, respectively, at the apices 36 thereof, and extend upwardly and thence downwardly towards the rear of the garment, at which location the straps are operatively connected to the thorax-engirdling portions 26 and 28, respectively. At the rear of the garment 10, the thorax-engirdling strap 30 comprises stress straps 38 and 40 which are operatively connected to the thorax-engirdling portions 26 and 28, respectively, of the cups 12 and 14, at the same location at which the shoulder straps 32 and 34 are operatively connected to these portions, and extend from that location to a location corresponding with the position of the termini of the strap 30 at the rear of the garment. The stress straps 38 and 40 are, therefore, disposed in at least a partially overlapping relationship with respect to the strap 30, and are operatively connected thereto in any suitable manner, so that a portion of the strap at the rear of the garment comprises a plurality or multiplicity of layers of material. It will, of course, be understood that the straps 38 and 40 preferably are fabricated of the same material from which the strap 30 is fabricated, though they may be fabricated of different materials. Accordingly, the garment 10 is more than adequately capable of accommodating the forces applied thereto by the bust, which are transmitted from the front of the garment towards the rear thereof at least partially by the shoulder straps 32 and 34.

The significance of fabricating a garment constructed in accordance with the principles of this invention of an unusually light-weight material has hereinbefore been pointed out. Accordingly, the breast receiving cups 12 and 14, comprising the breast receiving portions 22 and 24, and the thorax-engirdling portions 26 and 28, are each of them preferably fabricated of a material such as nylon-tricot, or other similar material having substantially the same desirable characteristics of unusually light-weight, softness, flexibility and pliability, and being capable of readily circulating air therethrough. As pointed out above, heretofore it was considered impractical, if not impossible, to fabricate a garment of the type to which the present invention pertains from a material of such light-weight, since it was considered highly unlikely that a brassiere fabricated of such a material could properly and adequately perform its intended functions. To enable a brassiere to more than adequately perform its intended functions and yet be fabricated of a material of unusually light-weight, such as nylon-tricot, a garment constructed in accordance with the principles of the present invention comprises the breast receiving portions 22 and 24 of the bust cups 12 and 14, respectively, each of which breast receiving portions comprise, in turn, a dart or seam 42 and 44, respectively. The darts may be fabricated into the breast receiving portions 22 and 24 in any suitable manner, and, for example, may be defined by a row of stitching 45 that connects together overlapped portions of the material from which the breast receiving portions are fabricated.

It has been found that in order to enable a brassiere to more than adequately and handsomely perform its intended functions, while yet being able to fabricate the garment from an unusually light-weight material, such as nylon-tricot the longitudinal dimensional extent, the contour or configuration, the direction in which it extends, and the location of the darts in toto, as well as the location of its termini, are of particular importance. This is true since, as is considered readily apparent, the stress applied to each of the bust receiving cups 12 and 14 of the garment 10 is exerted through the center of gravity of each of a corresponding one of the breasts of a female torso particularly adapted to be disposed therewithin. Thus, and with reference first to the dart 42, one of the terminal locations 46 thereof is located laterally to one side of the apex 36, with the terminal location 48 thereof being located laterally to the other side of the apex at the thorax-engirdling strap 30. The location of the termini 46 and 48 is, in addition, such that the longitudinal dimensional extent of the dart is greater than one-half of the vertical dimensional extent of the breast receiving portion 22. Still further, the dart 42 is of curvilinear configuration. Of the utmost importance, however, is that the direction of the dart 42 of the breast receiving portion 22, or its locus, is such that the dart lies wholly within the fourth quadrant of a pair of coordinate axes whose origin is disposed at the terminal location 46, as opposed to the dart being located within the first, second or third quadrants, it being understood that the quadrants of a pair of coordinate axes are denominated in a counter-clockwise direction, as opposed to being denominated in a clockwise direction. By satisfying each and every one of the foregoing criteria of the dart 42, it has been found that the force exerted by the breast particularly adapted to be disposed within the breast receiving 22 through its center of gravity will be applied to the dart, as opposed to being applied to the body of the breast receiving portion, and that the resulting stress will be transmitted along the dart to the distensible thorax-engirdling strap 30, and thence rearwardly of the garment 10 enabling the stress to efficiently be dissipated. The main or major portion, or body of the breast receiving portion 22 will not therefore be required to dissipate the stress resulting from the aforesaid force, thus enabling the breast receiving portion to be fabricated of the exemplary unusually light-weight material hereinbefore described, or other similar material having each and every one of the aforesaid characteristics. While some stress will be transmitted to the shoulder strap 32 and thence to the stress strap 38, and dissipated thereby, it has been found that the ability to fabricate the breast receiving portion 22 of an unusually light-weight material that is soft, flexible and pliable, and yet is more than adequately and handsomely capable of performing its intended functions, it is not affected.

The foregoing discussion pertaining to the dart 42 is equally applicable to the dart 44 of the breast receiving portion 24. In particular, one terminal location 50 of the dart 44 is located laterally to one side of the apex 36, and the other terminal location 52 located laterally to the other side thereof. The dart 44 is of substantially the same curvilinear configuration as the dart 42, and, of the utmost significance, is located in the third quadrant of a pair of coordinate axes having its origin at the terminal location 50, it being remembered that the quadrants defined by a pair of coordinate axes are denominated in a generally counter-clockwise direction. At this point, it will also be understood that the stress straps 38 and 40 assist in dissipating the stresses applied to a corresponding one of the breast receiving portions 22 and 24, and particularly with respect to the stresses transmitted along the darts 42 and 44 and thence along the thorax-engirdling strap 30, since the stress straps 38 and 40 are disposed in at least a partially overlapping relationship with respect thereto, and those stresses transmitted along the shoulder straps 32 and 34. To assist in dissipating those stresses trans-

mitted along the shoulder straps 32 and 34, they may be operatively associated with the apices 36 of the breast receiving portions 22 and 24 by means of distensible connectors 54.

It will now be understood that a foundation garment constructed in accordance with the principles of the present invention, such as the brassiere 10, comprises a plurality of breast receiving cups fabricated of an unusually light-weight material, each of which cups comprises, in turn, a breast receiving portion, and a thorax-engirdling portion. The breast receiving portions, in turn, comprise a dart or seam that is so disposed, positioned, located, contoured, and configured as to satisfy certain criteria. Specifically, each of the darts or seams are respectively disposed in that one of the quadrants defined by a pair coordinate axes having its origin at the uppermost terminal location thereof, enabling the darts to define or be denominated as "side" darts, as distinguished from being a dart or seam capable of a definition as a "vertical" dart, "frontal" dart, or a dart extending towards the center of the garment. Since the darts can be denominated as "side" darts, they in effect define radii or a circle, enabling the breast receiving portions of which they form a component part to present the characteristic of great supporting strength, while yet enabling them to be fabricated of an unusually light-weight material, an example of which, along with its characteristics, has hereinbefore been set forth. Additionally, a foundation garment constructed in accordance with the principles of the present invention, being fabricated of such light-weight material, enhances the female torso by presenting the very desirable aesthetic characteristics of not only being invisible through an outer garment, but in effect enabling the bust to appear as if it is ungarbed, further enabling the garment to present the bust in "nature's own way."

After reading the foregoing detailed description of an exemplary and illustrated form of the present invention, it will be understood that the objects set forth as the outset of this specification have successfully been achieved. And, while the invention has been shown, illustrated, described and disclosed in terms of an illustrated embodiment or modification which it has assumed in practice, the scope of the invention should not be deemed to be limited thereby, such other embodiments or modifications intended to be reserved especially as they fall within the scope of the claims here appended.

What is claimed is:

1. A foundation garment particularly adapted to be worn upon the female torso, comprising:
a plurality of breast receiving cups each comprising: a breast receiving portion having an apex; and a thorax-engirdling portion; said breast receiving portions being disposed in at least a partially overlapping relationship with respect to one another generally frontally of the garment to define a panel for operatively associating said breast receiving portions with one another of generally triangular configuration, and comprising a plurality of layers of material; a thorax-engirdling strap fabricated of a material that is distensible at least in a direction longitudinally thereof extending rearwardly of the garment having termini particularly adapted to be removably connected with respect to one another; and comprising; stress straps disposed in at least a partially overlapping relationship with respect thereto, and extending from a location at the termini of said thorax-engirdling strap towards each of said thorax-engirdling portions at the rear of said garment; and each of said breast receiving portions comprising: side darts extending from one terminal location disposed laterally to one side of the apex of said portions to another terminal location disposed laterally to an-

other side of said apices at said thorax-engirdling strap; said side darts being of curvilinear configuration, and having said one terminal location of each one thereof disposed within an upper-half of each of said breast receiving portions to define a longitudinal dimensional extent in excess of approximately one-half of the vertical dimensional extent of said portions; 5 said side darts being disposed only and wholly within a particular one of the quadrants defined by a pair of coordinate axes whose origin is located at said one terminal location which would enable said darts to transmit the stresses applied to said breast receiving portions to said thorax-engirdling strap, and thence rearwardly of the garment, with maximum efficiency, 15 further enabling said garment to dissipate said stresses with at least the same degree of efficiency.

2. A foundation garment as defined in claim 1, wherein:

said breast receiving portions and said thorax-engirdling 20 portions are fabricated of an unusually light-weight material.

3. A foundation garment as defined in claim 2, wherein: said light-weight material is a nylon-tricot, or other similar material, presenting the characteristics of an unusual degree of softness, flexibility, pliability, and the characteristics of invisibility through an outer garment, as well as enabling the bust to in effect appear naturally.

4. A foundation garment as defined in claim 3, wherein there is provided:

shoulder straps operatively associated with said breast receiving portions at the apices thereof, and extending rearwardly of the garment; said shoulder straps being operatively associated with said thorax-engirdling portions at the aforesaid location of the garment; and said stress straps being operatively associated with said thorax-engirdling portions and said shoulder straps.

5. A foundation garment particularly adapted to be 40 worn upon the female torso, comprising:

a plurality of breast receiving cups each comprising: a breast receiving portion, each having: a side dart extending from one terminal location disposed within a lower portion thereof to another terminal location disposed within a lower portion thereof.

6. A foundation garment as defined in claim 5, wherein:

said garment further comprises: a thorax-engirdling strap fabricated of a material that is distensible in at least one of a plurality of directions, and extending rearwardly of the garment; the other terminal location of said side darts being disposed at said thorax-engirdling strap, enabling the stresses applied to said breast receiving portions to be transmitted from said side darts thereto, and thence rearwardly of the garment.

7. A foundation garment as defined in claim 6, wherein:

said thorax-engirdling strap comprises: stress straps disposed in at least a partially overlapping relationship with respect thereto at a location rearwardly of the garment to assist in dissipating the stresses applied to said breast receiving portions.

8. A foundation garment as defined in claim 7, wherein:

8 said breast receiving portions are disposed in at least a partially overlapping relationship with respect to one another generally frontally of the garment to define a panel for operatively associating said breast receiving portions with one another, comprising a plurality of layers of material.

9. A foundation garment as defined in claim 8, wherein:

said breast receiving cups each of them further comprise:

a thorax-engirdling portion extending to a location disposed generally rearwardly of said garment; and wherein there is provided:

shoulder straps extending from the apices of said breast receiving portions to a location disposed generally rearwardly of said garment, and, at that location, being operatively associated with said thorax-engirdling portions;

said stress straps extending from said thorax-engirdling strap to the location at which said shoulder straps are operatively associated with said thorax-engirdling portions, and, at that location, being operatively associated therewith.

10. A foundation garment as defined in claim 9, wherein:

said breast receiving portions and said thorax-engirdling portions are fabricated of an unusually light-weight material.

11. A foundation garment as defined in claim 10, wherein:

said light-weight material is a nylon-tricot or other similar material, presenting the characteristics of an extreme degree of softness, flexibility, pliability, and the like.

12. A foundation garment as defined in claim 5, wherein:

such breast receiving portion, comprises: an apex; and wherein each side dart extends from one terminal location disposed laterally to one side of the apex, to another terminal location disposed laterally to another side of said apex.

13. A foundation garment as defined in claim 12, wherein:

said side darts define a longitudinal dimensional extent in excess of substantially one-half of the vertical dimensional extent of said portions.

14. A foundation garment as defined in claim 13, wherein:

said side darts are of generally curvilinear configuration.

15. A foundation garment as defined in claim 5, wherein each breast receiving portion comprises an apex, and wherein said one terminal location is disposed laterally to one side of said apex, and said other terminal location is disposed laterally to another side of said apex.
